UNITED STATES PATENT OFFICE.

JOHN SOMMER, OF PEORIA, ILLINOIS.

DITCHING MACHINE.

1,420,876.

Specification of Letters Patent. Patented June 27, 1922.

Application filed February 6, 1920. Serial No. 356,639.

To all whom it may concern:

Be it known that I, JOHN SOMMER, a citizen of the United States, a resident of Peoria, in the county of Peoria and State of Illinois, have invented new and useful Improvements in Ditching Machines, of which the following is a specification.

This invention has reference to ditching machines, and relates particularly to that 10 type employing a revolving ditching wheel having buckets connected thereto, with which to do the digging.

One of the objects of the invention is to improve structures of this kind, by providing 15 a cleaner which passes through the buckets as the wheel is revolved, said cleaning means having the added function of opening the back end of the buckets during the cleaning operation.

20 The invention has for a further object to improve structures of this character, by providing the back ends of the buckets with swinging doors, or gates, which are opened through the action of the cleaning means 25 which passes through the buckets as the wheel is revolved, said cleaning means entering between and forcibly opening said doors, or gates.

A further object of the invention resides 30 in the knife structure adapted to be manually actuated for cleaning the insides of the rims of the buckets as the ditching wheel is rotated.

That the invention may be more fully 35 understood, reference is had to the accompanying drawings forming a part of the description, in which a preferred embodiment of the invention is shown, wherein,

Figure 1 is a side elevation of a ditching 40 wheel embodying my invention, a sufficient portion of the frame work being shown to show the support for said ditching wheel;

Figure 2 is an enlarged plan view of a 45 part of the ditching wheel, parts being broken away to show in plan, the means for forcibly swinging the doors or gates at the back ends of the buckets;

Figure 3 is an enlarged detail sectional 50 elevation as the same would appear if taken on the line 3—3, Figure 2, looking in the direction of the arrows;

Figure 4 is a detail showing the back end 55 of a bucket and my improved doors or gates hingedly connected thereto;

Figure 5 is a detail cross-section, in plan,

as the same would appear if taken on the line 5—5, Figure 4, and

Figure 6 is a vertical cross-section as the same would appear if taken on the line 6—6 Figure 3, looking in the direction of the arrow:

Like characters of reference denote corresponding parts throughout the figures.

In Figure 1 of the drawings, I have shown the frame work comprising the members 1, 2 and 3 which constitutes part of the general forward frame work of a ditching machine, provided with a revolving ditching wheel. The ditching wheel is designated 4 and it includes the spaced rings 5 preferably formed with internal gears 6 which mesh with the smaller pinions 7 receiving power from a shaft 8, on which is carried a sprocket wheel 9 engaged by a sprocket chain 10, actuated by a pinion 11 on a drive shaft 12, 75 adapted to receive its power from an engine or motor, and suitable driving mechanism supported or carried by the main frame work of the machine.

The frame work supporting the ditching 80 wheel includes a pair of trusses 13 constructed of the rails 14 and 15, and the braces 16, the inner ends of said trusses hung in a well known manner, to permit the same to be raised and lowered at their outer ends and 85 also raised bodily for positioning the ditching wheel relatively to its work. As the invention does not relate, per se, to the structural features of the frame, nor to the means for raising and lowering the trusses 13, no 90 further detailed explanation need be given to these elements of the machine.

17 designates the digging buckets of which there are a plurality, spaced around the ditching wheel and bowed so as to be secured 95 to the opposite rings 5 of said ditching wheel, in a well known manner and as shown in the drawings. The bodies of these buckets are solid throughout their lengths and widths, and at their forward ends are provided with a plurality of digging teeth 18. The back ends of these buckets are normally closed preferably by a pair of doors or gates 19, which extend down into the wheel between the rims and to a point approximately 105 in the same plane with the teeth of the gear wheels 6, formed or attached to said rings 5. Each door or gate is formed with a longitudinal opening 20 therethrough, protect- 110 ed by strengthening bosses 21 cast on oppo-

site sides of said doors or gates and with a plurality of laterally extended webs 22, to give transverse strength to said doors or gates.

- 5 When the doors or gates are in assembled position on the buckets, stems or spindles 23 pass down through the openings 20 and are secured in place by nuts 24, screwed on to threaded ends of said stems or spindles, 10 and seated within recesses 25 in the lower ends of said doors or gates. The stems or spindles 23 are connected to or form part of brackets or castings 26 secured to the inner walls of the buckets at their back ends 15 and braced by the outside plates 27.

In the normal closed position of the doors, or gates 19, the inner meeting edges are slightly spaced apart, as best seen in Fig. 4, which provides for the entrance therebetween of a wedge shaped end 28, of a cleaning bar 29 preferably T-shaped, which is supported in an inclined position, see Fig. 3, and sustained at one end by connections with a transverse, preferably channel frame 25 30, connected to the frame parts of the trusses 13. It is the function of the bar 29, with its wedge shaped end 28, to pass through the buckets as the digging wheel is revolved for the purpose of cleaning the buckets of 30 dirt, and it is the further function of said bar to enter between the doors or gates 19 as the wheel 4 is revolved, to positively oscillate or swing the said doors or gates 19 from the position shown in Fig. 4, to the 35 position shown in Fig. 6, which will permit the clearing of the buckets of the dirt elevated therein. The bar 29 is preferably located in line with the vertical axis of the wheel 4 at a point where the material may be 40 discharged from the buckets on to a transverse conveyor 31, shown diagrammatically in Fig. 6, and operatively carried through the trusses 13 between the braces 16.

The doors or gates are intended to be 45 swung approximately a quarter of a turn, which will be sufficient to open the back ends of the buckets, and to provide for the release of the material therein, and to limit the swinging of said doors or gates when forced 50 open by the bar 29, as explained, a shoulder 32 is preferably arranged at the top ends thereof, and is designed to come into contact with an off-set or shoulder 33 on the brackets or castings 26, best seen in Figure 5. The 55 doors or gates 19 assume a closed position when the buckets enter the ground and the dirt is forced thereagainst, as will be understood, and said shoulders 32 come into engagement with other off-sets 33.

60 In the event of the reverse rotation of the ditching wheel 4, as might be the case under certain circumstances, I provide for the swinging open of said doors or gates 19, as they approach contact with the lower end 65 of the bar 29, and this I accomplish by

means of the flanged plates 34 located upon opposite sides of the bar 29 and secured to the transverse channel beam 30, see Figure 2. The upstanding flanges of the plates 34 converge toward each other from a point 70 where the doors or gates 19 would come into contact therewith, if the wheel was reversed, as will be understood, by referring to Figure 2, the function of which, as will be understood, is to engage the body portions 75 of said doors or gates 19 near their outside edges as the wheel is rotated backwardly, moving the doors or gates in between the diverging portions of the flange plates 34, the flanges of said plates operating to swing 80 the said doors or gates open.

35 designate cutting knives located upon opposite sides of the wheel 4, adapted to be oscillated so as to move the same up and down between the rings 5 of the wheel, and 85 adjacent the inside of said rings. The lower ends of these cutting knives are connected with stems or spindles 36 which extend outwardly to the outside of the frame supporting wheel 4, and suitably journaled in bearings 37 secured to the trusses 13. To the outer end of one stem or spindle 36, is connected a lever 38 to be engaged by the operator or attendant, when he desires to oscillate the spindles or stems 36 to raise and 90 lower said cutting knives 35. To the outer end of the other stem or spindle 36 is connected a crank arm 39. This crank arm, as well as the lever, is connected by similar reach bars 40 with crank arms 41 secured on 100 the opposite ends of a short shaft 42, journaled in bearings 43 on the trusses 13.

It is obvious, that when an attendant engages the lever 38 and swings it into the position shown in Figure 1, that through the 105 connections which I have just described, the knives 35 will move up through the material elevated by the buckets and detach the same from the inside face of the rings 5. This movement of the knives may be made effective whenever desired by attendant, and the knives permitted to remain in the cutting position, or lowered as desired.

What I claim is:

1. In a device of the class described, in 115 combination, a bucket, a pair of gates to close the back end of the bucket, and cleaning means for the bucket which enters between and opens said gates.

2. In a device of the class described, in 120 combination, a bucket, a pair of gates to close the back end of the bucket, means to enter the bucket for cleaning the same, and also adapted to enter between and open said gates, and means to limit the opening movement of said gates.

3. In a device of the class described, in 125 combination, a bucket, a pair of gates to close the back end of the bucket, means to enter the bucket for cleaning the same, and 130

also adapted to enter between and open said gates, means to limit the opening movement of said gates, and a stop to limit the closing movement of said gates.

5 4. In a device of the class described, in combination, a bucket, digging means on the front end of said bucket, a pair of spindles connected to and extending across the back end of the bucket, and a gate swingably connected with each spindle.

10 5. In a device of the class described, in combination, a bucket, digging means on the front end of said bucket, a pair of brackets connected to the bucket at its back end and each having a depending spindle, and a gate swingably connected with each spindle.

15 6. In a device of the class described, in combination, a bucket, digging means on the front end of said bucket, a pair of gates for closing the back end of said bucket, means for hingedly connecting the gates to the bucket, and reinforcing ribs for said gate, said ribs extending longitudinally and laterally of said gates.

20 7. In a device of the class described, in combination, a revolute wheel, a plurality of buckets connected to said wheel, a pair of hinged gates to close the back end of each bucket, and means to enter between said

30 gates to open the same as the wheel is revolved.

25 8. In a device of the class described, in combination, a revolute wheel, a plurality of buckets connected to said wheel, a pair of hinged gates to close the back end of each bucket, and a member having a wedge end to enter between said gates to open the same as the wheel is revolved.

35 9. In a device of the class described, in combination, a revolute wheel, a plurality of buckets connected to said wheel, a pair of hinged gates to close the back end of each bucket, means to enter between said gates to open the same as the wheel is rotated in

40 one direction, and means to forcibly open

the gates when the wheel is rotated in a reverse direction.

10. In a device of the class described, in combination, a revolute wheel, a plurality of buckets connected to said wheel, a pair of 50 hinged gates to close the back end of each bucket, means to enter between each pair of gates as the wheel is revolved in one direction to open said gates, and means to engage the outside portions of said gates when the 55 wheel is revolved in an opposite direction to open said gates.

11. In a device of the class described, in combination, a wheel having spaced rings, buckets connecting said rings, a pair of 60 knives pivotally supported to be oscillated between and adjacent to said rings, a lever, operating connections between said lever and said knives, and cleaning means normally disposed in an inclined position midway between said knives and adapted to enter said buckets as the wheel is revolved.

12. In a device of the class described, in combination, a bucket, digging means on the front end of said bucket, a pair of hinged 70 gates to close the back end of the bucket, and means to limit the opening movement of said gates.

13. In a device of the class described, in combination, a revolute wheel, a plurality 75 of buckets connected to said wheel, digging means on the front end of each bucket, and a pair of hinged gates to close the back end of each bucket.

14. In a device of the class described, in 80 combination, a revolute wheel, a plurality of buckets connected to said wheel, digging means on the front end of each bucket, a pair of hinged gates to close the back end of each bucket, and means to limit the opening 85 movement of said gates.

In witness whereof I have hereunto affixed my hand this 31st day of January, 1920.

JOHN SOMMER.
